UNITED STATES PATENT OFFICE

ABRAHAM J. KUSEL, OF BALTIMORE, MARYLAND, ASSIGNOR TO KULAIR CORPORATION,
A CORPORATION OF DELAWARE

REFRIGERATING VALVE AND METHOD OF CONSTRUCTING THE SAME

Original application filed June 28, 1924, Serial No. 722,985. Divided and this application filed April 26, 1926. Serial No. 104,855.

This application is a division of my application filed June 28, 1924, and given Serial No. 722,985.

There exists in the present practice of refrigerating machine construction certain recognized defects which I have overcome in my invention.

Refrigerating practice demands valves which shall provide at all times an absolute seat on both the discharge and inlet sides as well as incorporate such features as to eliminate constrictive influence or wire-drawing of the medium passing through the valves in operation; in addition, there is the desire to make such valves practically noiseless in operation and to provide a valve that may be readily and cheaply assembled and yet be of such construction and accuracy as will permit of self-aligning elements so as to provide all of the aforementioned advantages.

A further object of my invention is the process of self-alignment of the valves and maintaining the same as hereinafter set forth.

A further object of my invention is the construction of a valve embracing the desired features above enumerated and yet so simple and easily made that ordinary stamping and screw machine processes may be employed.

Of course, standardization under modern machine practice is understood.

A further object of my invention is the construction of a suction valve that will possess larger internal clearances and yet be no larger externally than the companion discharge valve in order to fit uniformity of ports, a desirable feature in refrigeration.

A further object of my invention is the providing of a valve unit in which the valve is completely and finally assembled and adjusted prior to insertion in the operating refrigerating machine.

With the foregoing objects in view, my invention consists of the methods employed, combination and arrangement of systems, apparatus and means as hereinafter specifically provided and illustrated in the accompanying drawings wherein is shown the preferred embodiment of my invention, but it is understood that changes, variations and modifica-

tions may be resorted to which come within the scope of the claims hereunto appended.

In the drawings of the herein-described embodiment of my invention, Fig. 1 is a sectional view in elevation of the suction or inlet valve of a refrigerating machine; Fig. 2 is a sectional view in elevation of the discharge or outlet valve of a refrigerating machine, embracing my improvements; Fig. 3 is a plan view of the so-called "spider", in my construction; and Fig. 4 is a view in elevation of the spider shown in Fig. 3.

Similar numerals refer to similar parts throughout the several views.

Referring to the drawings in detail, with reference first to Fig. 1 which shows an intake or suction valve, the improved valve assembly comprises a removable cylindrical member 22, supporting in operative position a valve 20, the stem 24 of said valve being guided and maintained concentrically of the cylindrical member 22 by spacing devices or spiders 25. These spiders 25 are provided with enlarged central portions 26 forming sufficient bearings for the valve stem 24 during the operation thereof. The valve 20 is normally maintained in closed position by a compression spring or the like 23 mounted about the lower end of the valve stem 24 and held in position between the lowermost spider 25 and the end of the valve stem 24 by a washer or the like 23'.

Upon referring to Fig. 2 there is shown a reversely operating valve to that shown in Fig. 1 and in this instance the cylindrical member 22 is provided with an elongation 22' in order that the spiders or guides 25 may be properly spaced apart to permit the insertion of the spring 23 between the upper face of the lowermost guide and the washer 23' which washer in this instance is located near the upper end of the valve stem 24 which alternative construction as distinguished from that shown in Fig. 1 is obviously necessary owing to the apparent operation of the valve.

The general construction and assembling of the valve units however are the same and are covered by the same invention. In each instance the entire valve including its seat is

assembled prior to its installation and can be inserted and removed as a unit.

In the construction of the spider 25, shown in Figs. 3 and 4, stampings are used and are placed within the casing 22 and pressed therein by a tool positively centering the same and pressing the same into intimate contact with said casing; this aligning and setting simultaneously by positive means insures accuracy of both setting and aligning, and is an inexpensive method of making such assemblage.

In the manufacture of the spiders, or guides, a distortion is occasioned which provides a means for securing the guides within the shell when said distortion is corrected by a centering means.

In this description and claims, when I use the term "spider," I mean a spacing element.

Having thus described my invention, what I claim and desire to secure by Letters Patent is:

1. A unitary valve structure comprising a removable cylindrical member forming a valve seat, a valve and stem, spaced guideways for concentrically mounting said valve within the cylindrical member, both of said guideways being frictionally maintained in definite spaced relation but removable from said cylindrical member and a spring for maintaining the valve normally closed and in assembled operative position with respect to said cylindrical member.

2. A unitary valve structure comprising a removable cylindrical member forming a valve seat, a valve and stem, spaced guideways carried by the cylindrical member for concentrically and positively mounting said valve in the cylindrical member with respect to the valve seat, both of said guideways being frictionally maintained in definite spaced relation but removable from said cylindrical member and a spring for maintaining the said valve normally closed and in assembled operative position with respect to said cylindrical member.

ABRAHAM J. KUSEL.
